UNITED STATES PATENT OFFICE

133,779

DESIGN FOR A COMBINED LIPSTICK CONTAINER AND LIPSTICK

Eleanor Kairalla, New York, N. Y.

Application May 16, 1941, Serial No. 100,977

Term of patent 7 years

To all whom it may concern:

Be it known that Eleanor Kairalla, a citizen of the United States and resident of New York city, in the State of New York, has invented a new, original, and ornamental Design for a Combined Lipstick Container and Lipstick, of which the following is a specification, reference being had to the accompanying drawing forming part thereof, in which

Fig. 1 is a perspective view of the combined lipstick container and lipstick embodying my new design, in closed position; and

Fig. 2 is a perspective view thereof in open position.

I claim:

The ornamental design for a combined lipstick container and lipstick, substantially as shown.

ELEANOR KAIRALLA.
